(57) **CLAIM**

The ornamental design for coffee maker, as shown and described.

DESCRIPTION

FIG. 1 is a perspective view as seen from the top, front and left side of a coffee maker showing a preferred embodiment of the new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a right side elevational view thereof;

FIG. 7 is a perspective view as seen from the top, front and left side of a coffee maker showing a second embodiment of the new design;

FIG. 8 a left side elevational view of the coffee maker shown in FIG. 7;

FIG. 9 is a front elevational view of the coffee maker shown in FIG. 7;

FIG. 10 is a rear elevational view of the coffee maker shown in FIG. 7;

FIG. 11 is a top plan view of the coffee maker shown in FIG. 7;

FIG. 12 is a right side elevational view of the coffee maker shown in FIG. 7;

FIG. 13 is a perspective view as seen from the top, front and left side of a coffee maker showing a third embodiment of the new design;

FIG. 14 is a left side elevational view of the coffee maker shown in FIG. 13;

FIG. 15 is a front elevational view of the coffee maker shown in FIG. 13;

FIG. 16 is a rear elevational view of the coffee maker shown in FIG. 13;

FIG. 17 is a top plan view of the coffee maker shown in FIG. 13;

FIG. 18 is a right side elevational view of the coffee maker shown in FIG. 13;

FIG. 19 is a perspective view as seen from the top, front and left side of a coffee maker showing a fourth embodiment of the new design;

FIG. 20 is a left side elevational view of the coffee maker shown in FIG. 19;

FIG. 21 is a front elevational view of the coffee maker shown in FIG. 19;

FIG. 22 is a rear elevational view of the coffee maker shown in FIG. 19;

FIG. 23 is a top plan view of the coffee maker shown in FIG. 19; and,

FIG. 24 is a right side elevational view of the coffee maker shown in FIG. 19.
